UNITED STATES PATENT OFFICE.

PETER FISCHER, OF FORT ADAMS, MISSISSIPPI.

CROSSCUT-SAWING MACHINE.

Specification of Letters Patent No. 31,535, dated February 26, 1861.

To all whom it may concern:

Be it known that I, PETER FISCHER, of Fort Adams, in the county of Wilkinson and State of Mississippi, have invented a new and Improved Crosscut-Sawing Machine for Sawing Logs into Cord or Fire Wood; and I do hereby declare that the following is a full, clear, and exact description of the same, reference being had to the annexed drawings, making a part of this specification, in which—

Figure 1, is a side view of my invention; Fig. 2 a transverse vertical section of the same taken in the line x, x , Fig. 1.

15 Similar letters of reference indicate corresponding parts in the two figures.

This invention relates to a new and improved portable cross-cut sawing machine designed for sawing felled timber into cord 20 or fire wood and also into proper sized bolts for cutting into shingles, staves, etc.

To enable those skilled in the art to fully understand and construct my invention I will proceed to describe it.

25 A, represents a frame which is composed of a series of horizontal bars a , connected by traverse pieces b , and supported by legs c, c' , the legs c , at one side of the frame being vertical and fitted in mortises d , in the bars a , 30 so that the frame may be raised and lowered thereon. The legs c' , at the opposite side of the frame are inclined, the bars a , which are in contact with them being recessed to receive them as shown at e , in Fig. 2. The 35 frame A, is secured on the legs c, c' , at any desired point by pins f . The lower ends of the legs c' , are provided with rollers g .

On the upper part of the frame A, there is placed a shaft h . This is the driving 40 shaft and it has a spur wheel i , on it which gears into a pinion j , on a shaft k , below the shaft h . The shaft k , may be provided with

a fly wheel l , and at one end it has a crank m , attached. The crank m , has a connecting rod n , secured to it the front end of said rod 45 being attached to a bar o , the upper end of which is secured by a pivot or bolt p , to the upper part of one of the legs c . The bar o , passes through a guide q , attached to the frame A, and to the lower end of the bar o , 50 the saw B, is attached by a pivot or bolt r .

The operation is as follows: The frame A, is adjusted to the log to be sawed in such a way that the legs at its front end will be against the log or quite near to it and the 55 frame is leveled by adjusting the legs c, c' , so as to compensate for any unevenness of the ground, the leg c , to which the bar o , is attached being separately adjusted higher or lower as the diameter of the log may require. 60 The shaft h , is rotated by any convenient power and motion is communicated therefrom to the shaft k , by the gearing i, j . The crank m , by its rotation communicates, 65 through the medium of the bar o , a reciprocating motion to the saw, B, which acts upon the log feeding itself to its work by its own gravity.

I am aware that portable reciprocating saws have been operated by means of a 70 crank, and arranged in various ways. I do not claim broadly such device irrespective of the construction and arrangement herein shown and described. But

I do claim as new and desire to secure by 75 Letters Patent—

The arrangement of the saw driving gearing, bar o , and saw B, with the adjustable leg c and legs c' in the manner and for the purposes herein shown and described.

PETER FISCHER.
